SOFA-BED MECHANISM WITH ANTI-TOPPLE MEANS

Louis Pokorny, Jr., Ronkonkoma, N.Y., assignor of one-third to Louis Pokorny, Ronkonkoma, and one-third to John M. Pokorny, Bellport, N.Y.

Filed Dec. 28, 1962, Ser. No. 248,016
2 Claims. (Cl. 5—13)

This invention relates to sofa-beds, and has particular reference to an improvement that contributes to a stabilization of the structure during the unfolding and refolding of the mechanism.

The type of sofa-bed mechanism with which the invention is primarily concerned comprises sections that are pivoted to one another in succession and are foldable between a collapsed sofa position and an extended bed position, the sections including two which lie in superposed horizontal planes when the structure is collapsed and in horizontal alignment when the mechanism is extended. These sections may be conveniently designated upper and lower horizontal sections. The lower section is pivotally joined to a rear section, which is in turn connected to a fixed sofa body, and the upper and lower horizontal sections are connected at the front by means of a section that lies vertical in the sofa-defining position and may therefore be designated a front vertical section.

My earlier patents, Nos. 2,832,965 and 3,005,211 show examples of this kind of mechanism. In the folded position, the entire mechanism is accommodated within a sofa body which is usually upholstered, and includes removable seat cushions. In the extended position, the mechanism stretches forwardly from the sofa body, together with a mattress coextensive and foldable with the mechanism, to define a bed. The linkage systems described in those patents are of the general type to which the present invention relates; they interconnect the sections in such a way that the mechanism is constrained to fold and unfold in accordance with a predetermined pattern of movement.

It is often desirable to mount a mechanism of this kind in a sofa body in such a way that the mechanism will unfold forwardly to an increased extent. One reason may be to minimize conflict between the mechanism and the upholstery on the back of the sofa body; another may be to define a longer bed. In any case, under such circumstances, the center of gravity of the mechanism in its intermediate positions shifts forwardly, and this influences the structure to topple forwardly as it is being opened or closed. During the closing procedure this tendency may be increased by the fact that during the period of greatest instability the user is likely to be exerting a downward pressure upon the partially re-folded mechanism, thus aggravating the instability. Moreover, the current trend toward use of lighter-weight materials in forming the sofa body reduces the ability of the sofa body to serve, by its weight, as a stabilizing influence. It is the object of the present invention to prevent such instability and to eliminate any toppling tendency during the folding and unfolding operations.

In achieving this objective, the invention relies in part upon a leg which is commonly employed in the intermediate region of the extended frame. As shown and described in each of my aforesaid earlier patents, this leg is adapted to extend rearwardly and to lie close to the lower horizontal section in the folded condition of the mechanism, and it rotates to a vertical operative disposition during the unfolding procedure. It is an objective of this invention to provide improvements in the operating linkages whereby the leg reaches its vertical disposition at an earlier stage during the unfolding operation, and leaves its vertical floor-contacting disposition at

2

a later stage during the folding operation. In this way, floor-contacting support is afforded sooner as the unfolding is carried out, thus propping the structure and preventing topple; and during the restoration of the parts from bed to sofa the supporting benefit of the leg is retained until the mechanism has been re-folded beyond the potentially unstable posture.

A more particular object of the invention is to achieve the desired results by a mechanism which is entirely practical from a manufacturing standpoint, does not materially increase the cost of manufacture, and functions reliably over long periods of use.

A preferred way of attaining these objectives and advantages is illustrated in the accompanying drawings, in which—

FIG. 1 is an end view of a sofa-bed mechanism having the improvements of the present invention, the sofa body, the cushions of the sofa, and the mattress of the bed, being shown in dot-dash lines, the mechanism being shown in its fully folded position;

FIGURES 2-6 are views in the same direction as FIG. 1, showing the mechanism in successive stages of opening, parts being omitted in certain cases for the sake of compactness of illustration; and

FIGURE 6A is a detail cross-section on line 6A—6A of FIG. 6.

The sofa body within which the mechanism is mounted includes the usual upholstered back 10, sides 11, removable seat cushions 12, legs 13, and a front board 14 which remains fixed in position and extends along the entire length of the sofa. In addition, there is a movable front board 15 mounted on the sofa-bed mechanism and carried along with it when it is unfolded. The front boards 14 and 15 and the sides 11 may or may not be upholstered depending upon the style of the sofa.

The sofa-bed mechanism includes four sections pivoted to one another in succession, and a linkage system interconnecting them. In the fully folded condition the sections assume the relative positions shown in FIG. 1. It will be understood that these sections extend for substantially the full length of the sofa from one side 11 of the sofa body to the other, and that the pivotal anchorages of the mechanism to the sofa body are provided in duplicate, one at each side. In the drawings only one side 11 is shown.

The sections of the mechanism comprise a rear section 18 connected by a link 16 to a fixed pivot 27 on the sofa body. The link is pivoted to the rear section 18 at the upper end 17 of the latter. At its lower end the section 18 is pivoted at 22 to the lower horizontal section 19. The section 19 is pivoted at 23 to the front vertical section 20 (see FIGS. 5 and 6), and the latter is pivoted to the upper horizontal section 21 at 26. These pivotal connections and mountings permit the mechanism to be withdrawn from the sofa body into an extended condition (FIG. 6) in which the four sections lie in horizontal alignment to define a bed.

Extending across the sections in known fashion is a bed spring (not shown), attached to them in any suitable manner. It supports a mattress 29 which is coextensive with the mechanism and folds with the latter into the compacted condition shown in FIG. 1. In this position the bed spring and the mattress serve to support the seat cushions 12.

Pivoted to the rear section 18, at 28, is an actuating link 30 which will be referred to herein as a "rear link" to distinguish it from a "front link" hereinafter to be described. The pivot 28 lies just forwardly of the rear end of the link 30, and a connecting link 31 is pivoted at 32 to this rear end and extends upwardly to a pivot connection 33 with the anchoring link 16. The pivot 33 lies slightly spaced from the pivot 17.

The front end of the rear link 30 is pivotally connected at 34 to one arm of a lever 35 medially fulcrumed on the lower horizontal section 19. This lever is an important element of the improved linkage to which this invention relates. It is most clearly seen in its entirety in FIGS. 5 and 6. Its pivotal connection to the section 19 is at 36. For simplicity of manufacture the lever may be formed of two parts rigidly riveted together, as shown. The arm to which the rear link 30 is connected extends, in effect, from the pivot 34 to the fulcrum 36. The other arm extends from the fulcrum 36 to the pivot A presently to be referred to in more detail. In the construction illustrated, these lever arms are at a slight angle to each other so that the lever is of the bellcrank type.

The lever 35 is formed to define a leg 38 preferably provided with a caster 39 at its end. This leg is adapted to extend rearwardly and to lie closely alongside the lower horizontal section 19 when the mechanism is fully folded as shown in FIG. 1. The leg 38 rotates about the pivot 36 toward a vertical disposition as the mechanism is unfolded, and in the fully extended condition of the mechanism the leg 38 serves as a medial bed support as indicated in FIG. 6.

For convenience the lever 35 will be referred to hereinafter as a "first lever." A second lever 40, also constituting an element of the improved linkage, is medially fulcrumed on the front vertical section 20. The pivot connection is designated B (FIGS. 5 and 6). It is preferably formed in a bracket (FIG. 6A) which is rigidly secured to the section 20 and projects laterally therefrom.

The lever 40 is also of the bellcrank variety in the embodiment herein chosen for illustration. Its forwardly extending arm extends from the fulcrum B to the pivot 42 at which the front link 43 is connected. This link extends to the upper horizontal section, as best indicated in FIGS. 1-4, being pivotally connected to it at 44. The rear arm of lever 40 extends from the fulcrum B to the pivot 46.

The desired objectives of the invention are attained by providing a special articulation, of collapsible character, between the first lever 35 and the second lever 40. The purpose of the articulation is to delay the activating effect of these levers upon each other so that, during the unfolding operation, the leg 38 reaches its vertical disposition at an earlier stage than it otherwise would, and so that, during the re-folding operation, the leg 38 will remain down for a longer period than it otherwise would.

The collapsible articulation between levers 35 and 40 is preferably a connecting link 45 pivoted to the first lever 35 at point A and to the second lever 40 at point 46. The link 45 has an extension 48 beyond the point 46 which moves toward and away from an abutment 47 formed on the lever 40. The extension 48 moves away from the abutment 47 whenever the first lever 35 presses forwardly against pivot A, which occurs during the unfolding of the mechanism, and whenever the second lever pushes rearwardly against pivot 46, which occurs during the re-folding operation. Conversely, the extension 48 moves against (and is stopped by) the abutment 47 whenever the first lever 35 presses rearwardly on pivot A (during the folding procedure), and whenever the second lever 40 pulls forwardly on pivot 46 (during the unfolding operation).

Before describing the operation of the mechanism, other parts of the linkage system should be described. Extending upwardly toward the rear link 30, and pivotally connected to it at 49, is an elevator arm 50 whose lower end is anchored at 51 to a fixed pivot on the sofa body. Extending downwardly beyond the pivot 51 is a short extension 50a rigidly riveted to or forming part of the elevator arm 50. A pair of tension springs 52 extend between the end 53 of this extension and a fixed anchorage 54 on the sofa body. In the fully closed condition of FIG. 1, the spring 52 exert a rearwardly upward pull on point 53 thus urging the elevator arm 50 upward, i.e., in a clock-

wise direction as shown in the drawings. This urging is counteracted by the weight of the mechanism. During the initial stages of unfolding movement the springs 52 thus thus counterbalance this weight and make it easier for the user to lift the mechanism to and beyond the position of FIG. 2. Similarly, during the re-folding operation the springs 52 facilitate the return movement of the parts from the condition of FIG. 4 to that of FIG. 3.

The front leg 58, pivoted to the upper horizontal section at 55, is automatically swung between the fully operative position of FIG. 6 and the fully retracted position of FIGS. 1-4 by a link 59 extending from it to the front link 43.

The movable front board section 15 is automatically swung between the normal position of FIGS. 1-4 and the lowered out-of-the-way position of FIG. 6 by links 56 and 57 deriving their activation from the lever 40 and the leg-actuating link 59.

The operation of the mechanism is as follows: After the sofa cushions 12 have been removed, the upper movable front board 15 is grasped to initiate an upward forward movement of the mechanism as a whole. Aiding in this movement are the springs 52. During the transition from FIG. 1 to FIG. 4, the pivot 17 at the upper end of the rear section 18 is constrained to move in a circular path around the fixed pivot 27; and the pivot 49 at the upper end of the elevator arm 50 is constrained to move in a circular arc around the fixed pivot 51. There is little change in the general relationship of parts during the movement from the condition of FIG. 1 to that of FIG. 2, but as the mechanism is moved through the stage shown in FIGS. 3 and 4 the angle between the sections 18 and 19 becomes more and more obtuse until finally these sections are in alignment. This causes the rear link 30 to move rearwardly with respect to the section 19, and the effect of this is to swing the first lever 35 in a counter-clockwise direction (as viewed in the present figures). Until the leg 38 has reached its fully operative position, as shown in FIG. 4, the rotative movement of the first lever 35 is ineffective in bringing about any swinging movements of the second lever 40, because of the collapsible articulation established by the link 45. But as the parts move toward the relationship shown in FIG. 5 the extension 48 moves toward and ultimately encounters the abutment 47, and during the subsequent opening movements there is a downward pressure upon the abutment 47, compelling the lever 40 to move counter-clockwise with respect to the section 20, thus pushing the front link 43 forwardly and ultimately bringing the parts into the fully extended condition shown in FIG. 6.

This same interaction takes place, in reverse, during the re-folding of the mechanism. During this operation the lever 40 presses rearwardly upon the pivot 46, but this is ineffective to rotate the lever 35 because the connecting link 45 is ineffective to transmit any force to the lever 35. This means that the leg 38 remains in the operative propping position shown in FIGS. 4-6 until after the parts have passed through the inherently unstable condition of FIG. 5 and have reached the compacted condition of FIG. 4. After this stage has been reached, the parts can be safely lifted into the condition of FIG. 3, and ultimately restored to the fully folded condition, without any danger of forward toppling.

Similarly, during the opening of the mechanism, the inability of the first lever 35 to rotate the second lever 40 allows the parts to be brought into the condition of FIG. 4 (with the leg 38 in supporting contact with the floor) before the inherent instability of FIG. 5 is reached. Once the leg 38 is down, the parts can be safely adjusted from the condition of FIG. 4 to and through the condition of FIG. 5, ultimately into the fully extended position of FIG. 6, without danger of toppling.

Viewing the operation from another aspect, it is to be noted that the mechanism allows the pivots A and B to move toward and away from each other. This relative

movement is made possible by the collapsible articulation herein described and illustrated.

It will be understood that many of the details shown may be modified by those skilled in the art without necessarily departing from the spirit and scope of the invention as expressed in the appended claims. Except as otherwise stated, therefore, it is intended that these details be interpreted as being illustrative only.

What is claimed is:

1. In a sofa-bed mechanism in which sections are pivot-
ed to one another in succession and include a rear sec-
tion, a lower horizontal section, a front vertical section
and an upper horizontal section, said sections being fold-
able between a collapsed position in which the lower and
upper horizontal sections lie in superposed parallel rela-
tion and an extended position in which said sections lie
in horizontal alignment: a linkage system interconnecting
said sections to constrain the mechanism to fold and
unfold in accordance with a predetermined pattern of
movement, said linkage system comprising—

a first lever fulcrumed medially to the lower horizontal
section and formed to define a leg,
said leg adapted to extend rearwardly and lie adja-
cent to the lower horizontal section in the folded
condition of the mechanism and to assume a
vertical disposition in contact with the floor in
the extended condition thereof,

a rear link extending between the rear section and
one arm of said lever,

5

10

15

20

25

a second lever fulcrumed medially to the front verti-
cal section,
a front link extending between one arm of said sec-
ond lever and the upper horizontal section,
and a collapsible articulation between the other arms of
said first and second levers, said articulation compris-
ing a connecting link pivoted at one point to the first
lever and at a second point to the second lever.

2. A sofa-bed linkage system as defined in claim 1, in-
cluding an abutment on said second lever, and an exten-
sion on said connecting link adapted to move toward and
away from said abutment and limiting the relative move-
ments of said levers in the direction that brings said ex-
tension against said abutment.
